UNITED STATES PATENT OFFICE.

WILLIAM A. WHITNEY, OF ROCKFORD, ILLINOIS, ASSIGNOR TO WHITNEY METAL
TOOL COMPANY.

HAND METAL-PUNCH.

Specification of Letters Patent.

Patented June 24, 1913.

1,065,752.

Application filed February 17, 1912. Serial No. 678,253.

To all whom it may concern:

Be it known that I, WILLIAM A. WHITNEY, a citizen of the United States, residing at Rockford, in the county of Winnebago and State of Illinois, have invented a new and useful Hand Metal-Punch, of which the following is a specification.

This invention relates to hand metal punches of that type wherein a stationary 10 and a movable handle are employed, the stationary handle having a slotted head provided with a transversely movable punch, the punch being operated by a member pivoted on the slotted head and engaging the 15 punch at its outer end, said member being operated by the movable or operating handle of the tool. Heretofore difficulty has been experienced in providing a satisfactory means of connection between the operating 20 handle and the tool engaging lever.

The object of the present invention is to provide an improved means for operating the tool engaging lever from the operating handle without undue wear, friction or binding.

With the foregoing and other objects in view which will appear as the description proceeds, the invention resides in the combination and arrangement of parts and in 30 the details of construction hereinafter described and claimed, it being understood that changes in the precise embodiment of invention herein disclosed can be made within the scope of what is claimed without departing from the spirit of the invention.

In the accompanying drawing forming a part of this specification,—Figure 1 is a side elevation of a portion of a punch constructed in accordance with the present invention; Fig. 2 is a similar view partly in section; Fig. 3 is a detail perspective view showing the end of the operating lever with the eccentric thereon; Fig. 4 is a perspective view of the outer end of the punch engaging member showing the circular bore in which the eccentric of the operating lever fits; Fig. 5 is a detail perspective view of an improved wear-receiving or washer member.

Like reference numerals indicate corresponding parts throughout the several figures of the drawing.

The numeral 1 indicates the head with which is connected the stationary handle 2. The head 1 is formed with a slot 3 intended

55 to receive the metal which is to be punched.

The slot 3 divides the head into arms or extensions 4 and 5. The punch 6 reciprocates through the extension 5 and passes into and out of a suitable socket in the extension 4. The punch 6 co-operates with a 60 socket member 6^a which is screwed into the extension 4, as shown in Fig. 2.

The means for actuating the punch includes a punch engaging member 7 which is pivotally connected at 8 with the head 1. 65 At its outer end, the punch engaging member 7, as best shown in Fig. 4, is provided with a punch engaging slot or opening 8, which receives the head 9 of the punch 6, as shown best in Fig. 2. The punch engaging 70 member 7 is also provided at its outer end with a circular bore or opening 10 which extends from side to side thereof and is provided with an annular slot 11. Fitting snugly in the bore 10 is a cylindrical member 12 with which is connected or formed integral, in any suitable manner, a main operating handle 13. The main operating handle 13 extends outward through the annular slot 11 in the bore 10. The cylindrical member 12 is formed with an eccentric bore 14 through which extends a bolt 15 which is connected at its opposite ends with a pair of metal straps 16. The straps 16, as best shown in Fig. 1, extend downward and are connected with a bolt 17, which passes laterally through the extension 5 of the slotted head 1. The bolts 15 and 17 are secured in place by any suitable means, such as for example, as the nuts shown in the drawing. For the purpose of assembling the cylindrical member 12 in the bore 10, one-half of said bore is split, as indicated at 18, in Fig. 4. This split portion extends from the outer end of the bore 10 to the end of the 95 slot 11 and serves to produce a tongue 12^a which is bent straight upward before the part 12 is inserted. With the tongue 12^a standing upward, the part 12 can be inserted 100 endwise into the bore 10 until the operating handle 13 is located in the slot 11. The tongue 10 is then bent down into the position shown in Fig. 4. By moving the operating handle 13 downward toward the stationary handle 2, the eccentric cylindrical 10 portion 12 of said handle throws the punch engaging member 7 downward, thus operating the punch.

When the punching tool passes through the metal, the handles of the punch usually 1

come together with a sharp knock and for the purpose of receiving the impact of this knock and preventing it from damaging the cast metal parts of the punch, a striker plate 22, shown in Fig. 5, is arranged upon the punch engaging member 7, as shown in Figs. 1 and 2. The striker plate 22 is provided with lateral wings 23 which terminate in washer-like portions 24. The washer portions 24 are disposed on opposite sides of the shank of the punch engaging member 7 and the bolt 8 extends through suitable openings in the washer portions 24. By means of this striker plate any damage to the punch engaging member 7, due to the impact of the operating handle 13, is avoided. Moreover, wear between the pivoted end of the member 7 and the lugs or ears on the slotted head 1 is taken up by the washer portions 24.

What is claimed is:

1. In a punch, the combination with a slotted head having a punching tool slideable therein, a punch engaging member pivotally mounted thereon and connected with said punching tool, an operating handle for actuating said punch engaging member, and means connecting said operating handle to said slotted head so as to permit swinging movement of the operating handle, of eccentrically connected operating members attached to the operating handle and the punch engaging member.
2. In a punch, the combination with a slotted head having a punching tool slideable therein, a punch engaging member pivotally mounted thereon and connected with said punching tool, an operating handle for actuating said punch engaging member, and means connecting said operating handle to said slotted head so as to permit swinging movement of the operating handle, of a rotary member eccentrically connected with said connecting means and said punch engaging member and said operating handle.
3. A punch having a slotted head provided with a punching tool, a punch engaging member pivoted on said head and en-

gaging said tool, said punch engaging member having a circular bore therein, a cylindrical member extending through said bore, straps eccentrically connected at one end to said cylindrical member and secured at the other end to said slotted head, and an operating handle rigidly connected to said cylindrical member.

4. A metal punch comprising a slotted head, a slideable punching tool therein, a punch-engaging member pivoted on said head at one end and engaging said tool at the other end, said member having a bore formed with a slot, the top wall of the bore being split longitudinally of the bore, from one end thereof to the slot, a cylindrical member fitted in said bore, an operating handle rigidly connected with said cylindrical member and extending through the slot in said bore, a bolt extending eccentrically through said cylindrical member, straps connected with said bolt at their upper ends and pivotally connected with said slotted head at their lower ends.

5. The combination with a punch having a slotted head, a punching tool, a tool engaging member pivoted on said head, and an operating handle for operating said tool engaging member, of a striker plate mounted on the back of said tool engaging member to receive the impact of said operating handle.

6. The combination with a punch having a slotted head, a punching tool, a tool engaging member pivoted on said head, and an operating handle for operating said tool engaging member, of a striker plate mounted on the pivoted end of said tool engaging member and having washer plates fitted against the opposite sides of said tool engaging member, for the purpose set forth.

In testimony that I claim the foregoing as my own, I have hereto affixed my signature in the presence of two witnesses.

WILLIAM A. WHITNEY.
